CLAIM

The ornamental design for a kitchen sink, as shown and
described.

DESCRIPTION

FIG. 1 is a front perspective view of a kitchen sink showing
my new design;

FIG. 2 is a top plan view thereof;

FIG. 3 is a left side elevational view thereof, the right side
elevational view being a mirror image thereof;

FIG. 4 is a front elevational view thereof; and,

FIG. 5 is a rear elevational view thereof.
